UNITED STATES PATENT OFFICE.

JOHN BARBOUR, OF BRAINTREE, AND JOHN A. BARBOUR, OF WOLLASTON,
MASSACHUSETTS.

RAND-PRESSING DIE.

SPECIFICATION forming part of Letters Patent No. 794,445, dated July 11, 1905.

Application filed August 25, 1904. Serial No. 222,101.

To all whom it may concern:

Be it known that we, JOHN BARBOUR, of Braintree, and JOHN A. BARBOUR, of Wollaston, in the county of Norfolk and State of Massachusetts, have invented certain new and useful Improvements in Rand-Pressing Dies, of which the following is a specification.

This invention has for its object to enable rand-strips for boot and shoe heels to be rapidly and economically formed or molded into the desired heel shape. A heel-rand is composed of a strip of leather which is wedge-shaped in cross-section and is applied to the side of a boot or shoe heel opposite the top lift, the rand giving the heel-seat portion of the heel the desired approximately concave form. It has long been customary to partially form a rand-strip by a crimping operation, which gives the rand-strip a curved form, partly adapting it to be conformed to the heel, the curved rand being subsequently conformed to the heel by hand. In some cases the rand has been given its complete and final shape by a machine which bends a straight rand-strip into heel shape and then applies the pressure to the bent strip to make the heel shape permanent. Each of the above-described methods is relatively expensive, the first because the amount of time required for hand-labor is considerable and the second because a relatively expensive machine is required for the operation.

Our invention provides means of simple and relatively inexpensive character adapted to complete the operation of forming a crimped or partially-curved rand-strip and give it the exact form required before its application to the heel.

The invention consists in the improved pressing means which we will now proceed to describe and claim.

Of the accompanying drawings, forming a part of this specification, Figure 1 represents a perspective view of the block hereinafter referred to containing a series of heel-shaped cavities. Fig. 2 represents one of the removable beds inserted in said cavities. Fig. 3 represents one of the loose followers which coöperates with the bottom of a cavity in

pressing a rand-strip. Fig. 4 represents a sectional view of the complete set of pressing devices. Fig. 5 represents a side view of a rand-strip partially formed as heretofore preparatory to its application to the heel. Fig. 6 represents a side view of a completed rand.

The same reference characters indicate the same parts in all the figures.

In the drawings, *a* represents a block, which is portable and is adapted to rest upon the bed of a suitable press, the block being preferably composed of cast-iron. In the block are formed a series of heel-shaped cavities *c*, each of which is open at one end. In each cavity *c* is loosely inserted a heel-shaped bed *b*, which is adapted to be raised from the cavity, one end of each bed preferably projecting from the open end of the corresponding cavity to form a handle, whereby the bed and a rand which has been pressed thereon may be quickly removed from the cavity. In connection with the bed *a* and its cavities we employ a series of heel-shaped followers *d*, each of which is insertible in one of the cavities. The opposed pressing-surfaces of the followers and of the beds *b* are shaped to conform to the wedge-shaped or triangular cross-section of the rand, the pressing-surface of the bed *b* being preferably flat, while the pressing-surface of the follower *d* is preferably beveled at its margin, as indicated at *d'*. The bed *b* and follower *d* are preferably made of metal and adapted to withstand the required pressure exerted upon the rand. The follower *d* projects above the block *a*, and the series of followers *d* are therefore adapted to receive the pressure of the platen of the press.

A rand-strip *s*, which has been crimped to a curved form, as indicated in Fig. 5, is placed within a cavity *c* and upon a bed *b*, inserted in the cavity, as indicated in Fig. 1. Ordinarily the resilience of the strip will cause it to press outwardly against the wall of the cavity, this pressure being sufficient to retain the strip in place in the cavity until it has been pressed. In case, however, the arms of the strip have a tendency to spring inward or away from the wall of the mold this tendency is prevented by studs *b' b'*, affixed to the bed *b*.

The follower *d* is then inserted in the cavity, said follower having recesses to receive the studs *b'*. When the several cavities of the block have been charged, as indicated, it is 5 placed upon the bed of the press and the platen of the press is brought down upon the followers *d*, the result being a compression of the rands, which flattens the wrinkles formed by bending the rands and makes permanent the heel 10 shape imparted to the rands by the walls of the cavities *c*. The pressure being removed, the block is removed from the press and the followers are removed from the cavities. The beds *b* are then lifted from the cavities, thus 15 releasing the completed rands.

As above stated and as shown in Fig. 1, one end of each bed *b* projects sufficiently from the open end of the corresponding cavity *c* to form a handle. These projecting portions or 20 handles of the beds enable said beds to be lifted directly upward from the cavities, so as to remove the completed rands conveniently and expeditiously. Said upward movement of each bed and a rand carried thereby results 25 in the clearing of the fixed stops *b'* herein-after referred to and which form part of the locking means to prevent slipping or lateral movement of the parts.

It will be seen that the described appliance 30 is extremely simple and inexpensive in construction. Any desired number of said appliances may be employed simultaneously in a press, the appliances being piled one upon another between the bed and platen of the 35 press, so that a large number of rands may be pressed simultaneously.

It will be observed that the bottom of the block *a* is flat. This not only enables the said block to be utilized to form a top plate for a 40 duplicate appliance, but it also insures the resting of the block flat and square upon the platen of a press. The removable members which occupy the cavities of the block *a* have a total thickness exceeding the depth of the 45 cavities in which they are to be placed, so that the upper surfaces of the followers *d* can project above the upper surface of the block *a*. The upper surfaces of the followers are all flat, and therefore they will be equally borne 50 upon by the bottom of the superimposed block when a plurality of the appliances are placed in a press.

We have found that by the use of this appliance we are enabled to materially reduce 55 the cost of forming the complete rands ready for application to boot or shoe heels as compared with the methods and means heretofore employed.

The bed *b*, which is preferably a thin plate 60 of metal, may be provided with the studs *b'* by suitably cutting the plate to permit portions of its material to be turned up, forming the studs *b'*. The opening thus formed in the plate may be utilized to engage fixed stops 65 *b'*, driven into the block *a* to prevent the end-

wise movement of the bed *b* out of the mold-cavity. To prevent the endwise movement of the follower *d* out of the mold-cavity, the bed *b* may be provided with an ear or stop *b'*, arranged to bear on the outer end of the follower. 70

Since the fixed stops *b'* project upward from the bottoms of the cavities in the block *a* through openings in the bed-plates *b*, the said bed-plates are practically locked, so as to be 75 held against lateral movement or a movement that would tend to slip the bed-plates out of the cavities, and the stud *b'* rising from the bed-plates and entering recesses in the followers *d* prevents any slipping movement of 80 the followers out of their proper positions in the cavities and on the bed-plates. When the beds are provided with ears or stops *b'*, said stops furnish additional locking means to prevent any slipping movement of the fol- 85 lowers.

While we have stated that the block *a* and followers *d* may be made of metal, we do not limit ourselves to this material. The block and followers may be in many cases made of 90 wood.

We claim—

1. A rand-pressing appliance comprising a block having a heel-shaped cavity, a heel-shaped follower adapted to enter the cavity, 95 and a removable bed fitting between the follower and bottom of the cavity, said bed being longer than the cavity so as to project therefrom and form a handle whereby a shaped rand may be lifted from the cavity. 100

2. A rand-pressing appliance comprising a block having a heel-shaped cavity, a heel-shaped follower adapted to enter the cavity, and a removable bed fitting between the follower and bottom of the cavity, said plate being longer than the cavity so as to project therefrom and form a handle whereby a shaped rand may be lifted from the cavity, the combined thickness of the follower and bed exceeding the depth of the cavity whereby the 110 appliance is adapted to be subjected to the action of a press. 115

3. A rand-pressing appliance comprising a block having a heel-shaped cavity open at one end, a loose heel-shaped bed insertible in the cavity and adapted to project from the open end thereof, and a heel-shaped follower adapted to enter the cavity, said block and bed having locking members to prevent endwise movement of the bed, the bed having also a 120 locking member to prevent endwise movement of the follower.

In testimony whereof we have affixed our signatures in presence of two witnesses.
